UNITED STATES PATENT OFFICE.

CHARLES E. NEWELL AND DAVID M. NEWELL, OF FRANKLIN,
PENNSYLVANIA.

PUMPING APPARATUS.

SPECIFICATION forming part of Letters Patent No. 595,965, dated December 21, 1897.

Application filed January 19, 1897. Serial No. 619,766. (No model.)

To all whom it may concern:

Be it known that we, CHARLES E. NEWELL and DAVID M. NEWELL, of Franklin, in the county of Venango and State of Pennsylvania, have invented a new and Improved Pumping Apparatus, of which the following is a full, clear, and exact description.

The invention relates to means for transmitting power to the pumps of oil and other wells.

The invention will be fully described hereinafter and defined in the claims.

Reference is to be had to the accompanying drawings, forming a part of this specification, in which similar characters of reference indicate corresponding parts in all the figures.

Figure 1 is a side elevation of one form of the invention, and Fig. 2 is a front elevation of the same form of the invention.

20 The invention is adapted to receive power from a motor and transmit the same to a pump. On a cement base *a* is mounted a block *b*, which has the form of a right-angled triangle. The base of the triangle is rested 25 on the base *a*, while the altitude of the triangle extends perpendicularly from the upper side of the base *a*.

A shaft *c* is held perpendicularly to the base *a* by means of boxes *b'* and *a'*. The box *a'* has 30 two sections, one of which rests directly against the vertical side of the block *b* and against the top of the base *a*, and the second or outer section of which has a right-angular form, one member being rested on the top of 35 the base *a* and the other member being abutted against the outer side of the first or inner section of the bearing. Running vertically 40 through the base *a* and through the horizontal member of the outer section of the bearing *a'* are tie-rods *a''*, which hold the outer section of the bearing *a'* immovably on the base. Running horizontally through the lower portion of the block *b* and through both 45 sections of the bearing *a'* are tie-rods *b''*, which force the box *a'* laterally against the vertical side of the block *b*. The box *a'* is by these means held firmly in the corner between the

top of the base *a* and the vertical side of the block *b*.

The box *b'* is formed of two sections embracing the shaft *c* and held firmly to the upper portion of the vertical side of the block *b* by means of tie-rods *b'''*. The shaft *c* turns freely within the boxes *a'* and *b'* and is stepped on ball-bearings *c'*. (Shown by dotted lines 55 in Fig. 2.)

Fixed to the upper portion of the shaft *c* is a pulley *d*, over which a belt *d'* passes. Also fixed to the upper portion of the shaft *c* is an eccentric *d''*. The power is transmitted to 60 the shaft *c* by the belt *d'* and is transmitted from the shaft by a pitman or other device coacting with the eccentric *d''*.

Having thus described our invention, we claim as new and desire to secure by Letters 65 Patent—

1. A power-transmitting apparatus having a base, a block seated on the base and having a side perpendicular to the base, bearings located one above the other and against the vertical side of the block, the lower bearing having two sections one of which directly engages the vertical side of the block, and the other of which has right-angular form with one member arranged against the first-named 75 section of the bearing and with the other member lying against the upper side of the base, tie-rods passed through the base and through the said second member of the outer section of the lower bearing, additional tie-rods passed through the bearing and through 80 both sections of the lower bearing, the upper bearing consisting in two sections the inner of which lies directly against the vertical side of the block and the outer of which lies against the inner section, tie-rods passed through the block and through both sections of the upper bearing, a vertical shaft held revolubly in the boxes, and means carried by the shaft, for receiving and transmitting movement therefrom, substantially as described.

2. A power-transmitting apparatus having a base, a block standing on the base, a first bearing engaging against the block, and

against the base, two rods for the said first bearing, one of said rods running through the base and having connection with the said first bearing, and the second of said rods running through the block and having connection with the said first bearing, a second bearing in line with the said first bearing and engaging the block, and an additional rod run through the

block and connected with the said second bearing.

CHARLES E. NEWELL.
DAVID M. NEWELL.
